UNITED STATES PATENT OFFICE.

EDWARD F. ANHOLZER, OF APPLETON, WISCONSIN.

BAKE TIN.

1,406,522.

Specification of Letters Patent. Patented Feb. 14, 1922.

Application filed December 20, 1920. Serial No. 432,049.

To all whom it may concern:

Be it known that I, EDWARD F. ANHOLZER, a citizen of the United States, residing at Appleton, in the county of Outagamie and 5 State of Wisconsin, have invented certain new and useful Improvements in Bake Tins, of which the following is a specification.

My invention has to do with pastry cutters used in bake tins.

10 It is the primary object of my invention to provide a cutter freely movable longitudinally and with an additional flexibility adapting it to use in rectangular pans or tins of irregular configuration. It is an additional object of this invention to provide a device particularly effective in cutting the pastry cleanly from tins having sharply angular corners and, at the same time, to provide a device which may be attached to 15 the tin without material modification thereto or which may be used therein without any change whatsoever.

These and other objects I have attained by the device illustrated in the accompanying drawings in which:

Figure 1 is a fragmental top view of a bake tin with my invention applied thereto, the dotted lines indicating the position of the cutter when rounding a corner therein:

30 Figure 2 is a vertical section of the invention:

Figure 3 is a similar view on the line 3—3 of Figure 2 looking in the direction of the arrows:

35 Figure 4 is a fragmentary view showing the invention attached to a false bottom instead of to the tin proper; and

Figure 5 is a perspective view of a different type of keeper member.

40 Like reference characters are used to designate similar parts in the detail description to follow and in the several views of the drawing above referred to.

The letter A is used to designate a rectangular bake tin. A cutter bar 6, having a length equivalent to at least one half the longer dimension of the tin but less than the shorter dimension thereof is arranged in said tin A so that it is pivoted substantially in 50 the center thereof.

A keeper member 7 comprising a body portion 8 and a projecting arm 9, in the preferred form of invention, is loosely connected to the bottom of the tin, the body portion 8 being inserted through an aperture

10 in the tin and retained in position by a head 11. The arm 9 is substantially at right angles to the body 8 and bent over the cutter bar 6, the free end of said arm being arranged to press upon the bottom of the tin 60 A. In this manner a track admitting of rectangular movement of the cutter bar 6 through the keeper member 7 is provided.

The keeper member is readily formed by using a "clinch rivet", cutting off one of the 65 prongs thereof and bending the remaining prong in the manner hereinbefore indicated.

Attached to the end of the cutter bar 6, adjacent the sides of the tin A, is another member which, for the purposes of this description, will be designated as the side bar 12. Said side bar is substantially Z-shaped, the lower horizontal portion being pivotally connected at 13 to the cutter bar 6 immediately adjacent its end. The upper horizontal part 70 has attached thereto a leaf spring member 14, the free end of which rests against the outside of the bake tin A to force the cutter or oblique portion tightly against the side of the tin A, said spring 14 preferably resting against the bead of the tin A to retain it in proper vertical adjustment.

In operation, the device is grasped by the upper horizontal portion of the side bar 12 and pushed along the edges of the bake tin. 85 The spring member 14 holds the oblique portion of the side bar rigidly against the inside of the tin so that the pastry is cut cleanly therefrom. When a corner is reached the side bar is forced therearound, 90 the spring member 14 serving to keep the side bar in close proximity with the sides of the tin.

During movement of the side bar the cutter bar 6 must necessarily also be moved. 95 Longitudinal movement thereof is provided by the keeper 7 which admits of a sliding movement of the cutter bar 6 therethrough to admit of the variations brought about by the changing position of the side bar 12.

As the side bar 12 is pushed along the edges of the tin, it necessarily produces, because of the changing position of the cutter bar 6, a rotary movement of the keeper 7, hence the pivotal connection of said keeper 105 member to the tin hereinbefore described.

When the cutter bar 6 is arranged parallel to any one of the sides of the tin A the side bar 12 will be in direct alignment therewith. But at no other time should said bar 12 be 110

in direct alinement with the cutter bar 6 for the maintenance of such an alinement would cause one of the cutting edges of the side bar 12 to be drawn away from the side 5 of the tin A thus preventing a clean cutting effect and defeating the very purpose of the invention. It will be noted that the cutter bar 6 and the side bar 12 are both flat and serve as knives. The pivotal connection 13 10 between said cutter bar 6 and side bar 12 admits of the side bar 12 remaining always flush with the sides of the tin A and of the use of sharp cutting edges thereon. Without this connection, it would be impossible 15 for the side bar 12 to always remain in close engagement with the sides of the tin A. The free sliding movement of the cutter bar 6 through the keeper 7 permits of the cutter bar 6 being moved longitudinally, 20 freely, to follow the side bar 12 in its journey around the sides of the tin A. The cutting function of said bar 6 is not in any way disturbed by the arrangement described, said bar being held against the bottom 25 of the tin A by the keeper 7.

In Figure 4, I have illustrated my device as attached to a plate 15 which may be also called a false bottom. In this arrangement of my invention, any bake tin may be employed and it will be unnecessary to perforate the bottom thereof to provide for pivotal connection of the keeper member. The purpose of my device is accomplished when I have provided an arrangement of 30 parts which admit of the side bar 12 being held flush at all points about the sides of the tin when manipulated therearound and it is immaterial to the success of the operation whether the keeper member is centrally 35 positioned or not. The pastry contained within the tin A will anchor the false bottom 15 in position to allow the side bar 12 and the cutter bar 6 to perform the functions intended for them.

40 In Figure 5 I have illustrated a specially formed keeper member 7'. This member comprises a body portion 8' and a laterally projecting arm 9' having on its under side a groove 6" to receive the cutter bar 6 and admit of its longitudinal movement in either 45 direction therethrough. A head 11' is provided to hold the keeper member 7' in any adjusted position upon the bottom of the tin or false bottom, whichever the case 50 may be.

Without the flexibility arranged for in my device, it is impossible for the side bar 12 to always remain in proper position upon the sides of the tin or to procure a clean 55 cutting of the pastry contained in the tin at and about sharp or angular corners therein. Where the tin has been distorted or bent in usage the side bar 12 clings to the side of the tin A and produces a clean cut. 60 When a false bottom is provided for my

cutting device, it is possible to use this invention in any shaped tin and to move the device from one tin to another as required.

While I have illustrated the preferred form and modifications of my invention, I 70 do not intend to limit myself to the specific forms herein described and illustrated; for modifications, alterations, and changes within the scope of the claims hereto appended are to be resorted to when desired. 75

Having thus described my invention, what I claim as new and desire to secure by Letters-Patent of the United States, is:

1. The combination with a pan, of a dough-loosening member comprising relatively movable sections, one of said sections operating over the bottom and the other of said sections operating over the side of said pan.

2. The combination with a receptacle, of a dough cutter comprising relatively movable sections and means for anchoring the cutter in co-operative relation to the receptacle.

3. The combination with a receptacle, of a dough-loosening member comprising relatively movable sections, and means co-operating with the wall of the receptacle to retain said member in operative relation thereto.

4. The combination with a receptacle, of a dough-loosening member comprising relatively movable sections, one of said sections operating over the bottom of the receptacle and having means for anchoring it thereupon, the other of said sections being adapted to operate on the side of said receptacle and having means for retaining it in operative position.

5. The combination with a receptacle, of a dough-loosening member comprising relatively movable sections, means for anchoring the member in the receptacle, and means for retaining the member in co-operative relation thereto.

6. The combination with a bake tin, of a pastry cutter comprising a main section, an anchoring member admitting of longitudinal and circumferential movement of said section over the bottom of the tin, and an extension section operating over the side of the tin and flexibly connected to said main section.

7. The combination with an oblong bake tin, of cutter elements loosely connected and adapted to operate over the bottom and sides of said tin, and an anchoring member therefor, the connection between the cutter elements admitting of the side element resting flat against the sides and corners of the receptacle when moved therealong.

8. The combination with a bake tin, of a longitudinal cutter element adapted to operate over the bottom of the tin, a vertical cutter element flexibly connected to said

bottom element and having an extension over the edge of the tin to form a handle, means carried by said extension to urge said vertical cutter element against the wall of the 5 tin, and an anchor member admitting longitudinal and circumferential movement of said longitudinal element.

9. A pastry cutter adapted to be used in a bake tin and comprising relatively movable 10 sections, one of said sections operating over the bottom of the tin, the other of said sections operating over the side of the tin, a keeper member admitting of longitudinal and circumferential movement of the cutter

to permit said cutter to follow the irregular 15 marginal contour of the tin, and a spring member to hold said cutter in frictional engagement with the side thereof.

10. The combination with a bake tin, of a cutter element composed of relatively movable 20 sections adapted to operate over the bottom and sides of the tin.

11. The combination with a bake tin of pivotally connected cutter elements adapted to operate over the entire area of the bottom 25 and the sides of the receptacle.

In testimony whereof I affix my signature.
EDWARD F. ANHOLZER.
